AUTOMATIC SAFETY REEL FOR AIRPLANE PILOTS

John C. Whittingham and Proctor W. Nichols,
Colorado Springs, Colo.

Application January 4, 1954, Serial No. 402,081

6 Claims. (Cl. 242—107)

This invention relates to improvements in safety devices for use more particularly by airplane pilots and passengers, but which is also adapted for use by automobile pilots and passengers and relates with greater particularity to an improved automatic reel mechanism for taking up the cable attached to a shoulder harness and for permitting the cable to be unreeled at a moderate speed to permit free movement of the pilot or passenger and which will automatically latch when the cable is subjected to a quick jerk thus preventing the person from being catapulted forwardly. As an example of such devices, attention is called to U. S. Patent 2,434,119, June 6, 1948.

It is the object of this invention to produce an automatic reel of the type indicated that shall be of light weight and of a comparatively simple construction.

Another object is to produce an automatic reel of the type indicated, which shall be provided with a spring rewind mechanism of such construction that it will exert a substantially constant torque at every stage of the unwinding and rewinding operation.

A further object is to produce a device of the type indicated that shall have means for effecting adjustments that will enable the latching of the reel to be adjusted to any desired rate of cable rewind acceleration.

The above and any other objects that may become apparent as the description proceeds are attained by means of a construction and an arrangement of parts that will now be described in detail, for which purpose reference will be had to the accompanying drawings in which the invention has been illustrated in its preferred form, and in which,

Figure 1 is a top plan view of the device, portions of the cover having been broken away to better disclose the construction.

Figure 2 is a section taken on line 2—2 Fig. 1 and shows the latch control mechanism in automatic lock position.

Figure 2a is a section also taken on line 2—2 of Fig. 1 and shows the latch control mechanism in manual lock position.

Figure 3 is a section taken on line 3—3 Figures 1 and 3.

Figure 4 is a fragmentary section taken on line 4—4 Figures 2 and 5.

Figure 5 is a side elevation looking upwardly in Figure 4.

Figure 6 is a fragmentary bottom plan view of the toothed lower surface of the rotary drum and a section of the friction pinion, taken on line 6—6 Figure 3.

Figure 6a is a fragmentary side elevational view of the rotary drum, looking through plane 6a—6a Figure 6.

Figure 7 is a fragmentary section taken on line 7—7 Figure 3.

Figure 8 is a section taken on line 8—8, Figure 3, and

Figure 9 is a fragmentary perspective view showing

2

a portion of the inner gear toothed surface of the rotor and its relation to the friction pinion.

Referring now to the drawing, reference numeral 10 designates a base which is preferably made from aluminum, magnesium or from some alloy of low specific gravity and is preferably a casting. The base is provided with an upwardly extending pivot 11. Surrounding the pivot and concentric therewith is a circular ridge 12 whose upper surface is provided with ratchet teeth 13. Surrounding the central pivot is an annular high power permanent magnet 14 of the Alnico type which has its poles at the top and the bottom. Mounted for rotation on pivot 11 is a drum which has been designated as a unit by reference number 15. The drum is circular and has a central hub 16. An annular recess is formed in the inner surface of drum 15 between the hub and the cylindrical wall 19 that is provided with gear teeth 18 that are inclined as shown in Fig. 9. The lower surface of the annular outer wall 19 is provided with ratchet teeth 13a which in the position of the drum shown in Fig. 2a interlock with teeth 13 on the raised portion 12 and latch the drum against rotation in the clockwise direction when viewed as in Fig. 1. The drum is made from magnetic material and when it is in the position shown in Fig. 2a the lower end of hub 16 will be in engagement with the upper surface of magnet 14 which serves to hold it in interlocked position until the drum is raised to the position shown in Fig. 2 by means which will be hereinafter described. The drum and the parts already described are enclosed by a removable cover 20 that is held in place by a screw 21 that has threaded engagement with pivot 11 as shown in Figures 1 and 3. Attached to the inner surface of the cover by screws 22 are annular magnets 23 that serve to hold the drum in its uppermost position as shown in Figures 2 and 3 until it is separated from the magnets by a force exerted thereon by a control means that will presently be described. A pivot 24 extends upwardly from the base as shown in Figures 3 and 6 and mounted for rotation thereon is a pinion 25 that has inclined or helical teeth that cooperate with teeth 18 on the drum. From Fig. 3 it will be seen that the upper end of the opening in pinion 25 is larger than the pivot so as to provide an annular space that is at least partly filled with a yieldable material 26 such as felt. A cup washer 17 is adjustably attached to the upper end of pivot 24 with its side edge resting on the felt packing that surrounds the pivot. By varying the compression of the felt or other equivalent packing material the resistance offered to the rotation of this pinion on the pivot can be regulated or adjusted to produce the optimum operation of the device. The outer or peripheral surface of the drum has two parallel grooves designated by numerals 29 and 30, the first mentioned groove being for the reception of cable 31. One end of the cable is attached to the drum in any suitable manner and is wrapped several times around the drum. In the drawing the cable has been shown as encircling the drum twice but any greater number of turns can be used. The cable passes to the outside through a tangential opening in the dust cover 32 and terminates in a ring 33 or equivalent means for effecting connection with the safety harness which has not been shown and is shown in many patents in Class 155—189.

The permanent magnets 23 serve to hold the drum in the position shown in Figures 2 and 3 while the magnet 14 holds the drum in the latched position shown in Fig. 2a. The position shown in Fig. 2 will be referred to as the automatic lock position and the one shown in Fig. 2a will be referred to as the manual lock position.

The control device will now be described. Attention has already been called to peripheral groove 30 with which the control device cooperates by means of pin 34 that projects from the slide 35. Projecting outwardly

from the other side of the slide are two vertically spaced pins 36 and 37 (Fig. 5). Slide 35 is guided in its movements in a channel formed by a metal strip whose shape is most clearly shown in Figures 4 and 5. The guide member is formed from sheet metal having a central outwardly facing guide channel whose side walls have been designated by 38 and 38a. Beyond the side walls 38 and 38a are inwardly facing channels whose outer walls have been designated by reference numerals 39 and 39a. Sides 40 and 40a are each provided with two vertically spaced openings 41 for screws 42 which secure the guide member to one side of the cover as shown in Fig. 1. The spaced channel walls are provided with aligned openings for the reception and guidance of the manual control cam member that extends through the last mentioned openings in the manner shown most clearly in Figures 2, 2a, 4 and 5 to which reference will now be had. Cam member 43 is constrained in its vertical movements by the slots in walls 39 and 39a as most clearly shown in Figures 2 and 2a and is provided on its top edge with a triangular cam 44 and is also provided on its lower edge with a cam surface 45. The distance from the lower edge of the cam member to the vertex of the triangular cam has been designated by *a* in Fig. 5 and is substantially equal to the clear distance between pins 36 and 37 and the end of the cam member to the right of cam surface 45 is also equal to *a*. The left hand end of member 43 projects to the outside of the cover when in the position shown in Fig. 2 as well as when the parts are in the position shown in Fig. 2a. A somewhat rigid push and pull wire 46 is connected to the left hand end of cam 43 and extends to the control lever 48 that has two positions, one corresponding to the automatic lock position shown in Fig. 2 and the other corresponds to the manual lock position shown in Fig. 1 and Fig. 2a. A spring 49 tends to keep lever 48 in each of its two positions. Wire 46 passes through a flexible tube 50 such as a closely coiled wire helix. A second wire 46a extends to a point near the pilot seat and terminates in a ring 51 or other equivalent hand grip that can be grasped by the pilot for controlling the latch device.

Flexible tubes 50 have one end anchored to bracket 51 by means of a clamp 52 and the other ends are also clamped by suitable means to a stationary member. The rocking of control handle 48 shifts the cam member between the two positions shown in Figures 2 and 2a. If cam member 43 is in the position shown in Fig. 2 it can be shifted to the locking position shown in Fig. 2a by a pull on hand grip 57.

It has been explained above that slide 35 has a pin 34 that projects into groove 39 and that slide 35 has two outwardly projecting pins 36 and 37. The relationship between pins 36 and 37 and the slide 43 has also been explained. When the parts are in the position shown in Figure 2 cam member 43 does not interfere with the downward movement of slide 35 and drum 15. When the cam member 43 is moved towards the left to the position shown in Figure 2a it forcibly moves drum 15 into locking position.

It is necessary that the drum shall be subjected to the action of a spring that will rotate it in a direction to wind the cable thereonto when the tension in the cable is reduced below a certain amount. The rewinding force is usually provided by a spring of the type used in clocks and such springs are shown in many patents and U. S. Patent 2,480,335 is an example. Such springs have a short range of operation in proportion to the space they occupy and one of their characteristics is that the torque exerted by them increases in direct proportion to the extent that they are wound. Instead of employing the usual clock spring type of spring another type is used which occupies less space and has the peculiar property of opposing a constant resistance to any force tending to unwind it. Such springs are old and have been selected

because their characteristic features make them most suitable for the function which they are to perform.

Referring now to Figures 3, 7 and 8, it will be seen that a pinion 51 which has been illustrated as provided with an integral hub 52 whose lower end is journaled in a bearing 53 in the base, is in operative engagement with gear 18 as shown in Fig. 7. Attached to the base at a point somewhat removed from hub 52 is a round pin 54 about which is mounted for free rotation a clock spring 55. The other end of the spring is anchored to hub 52 and by rotating pinion 51 and hub 52 in a clockwise direction the major portion of the spring is transferred onto hub 52. Since the spring has a permanent set that tends to coil it onto pin 54 it is evident that it must be bent in the opposite direction for winding it onto hub 52 and that it therefore has a tendency to return to pin 54. In this case there is no longitudinal tension applied to the spring. The theory on which this motor operates is well known and no further explanation will be given.

Operation

Assuming now that the device is attached to a pilot seat and that the connector 33 is attached to a safety harness in the usual way and assuming also that cam member 43 is in the automatic locking position shown in Fig. 2, and that the cable is fully wound onto the drum. By exerting a pull on the cable sufficient to unwind it from the drum the latter will turn in a clockwise direction and produce a corresponding rotation of pinions 25 and 51 thereby coiling more of spring 55 onto hub 52. When the tension in the cable is released the action of spring 55 will produce a counter-clock rotation of the drum. This free unwinding and winding of the cable permits the pilot to move about sufficiently to perform his duties. In the event of a threatened collision or of some danger, the pilot will move quickly and jerk the cable. The friction of pinion 25 and its inertia will cause a sufficient downward force to be produced by the interaction of the helical gear teeth to pull the drum away from magnets 23 and bring hub 16 into engagement with magnet 14 in which position the ratchet teeth 13 and 13a will interlock and prevent further rotation of the drum. This automatic locking of the drum prevents the pilot or passenger from being catapulted forwardly in the event of a sudden stop. To release the lock the operator moves the cam member 43 towards the left thereby returning pin 37 (which was moved downwardly to the level shown in Fig. 2a when the drum moved into locked position) and drum to the position shown in Fig. 2 in which position magnets 23 become effective and hold the drum from falling down until it is subjected either to a force produced by the interaction of the helical or inclined gear teeth or by a movement of the cam lever from the position shown in Figures 2 and 5 to the position shown in Fig. 2a. If the pilot or passenger is fearful of a possible sudden stoppage, the cam member is manually moved to the position shown in Fig. 2a by shifting lever 48 from the automatic lock position to the manual lock position shown in Fig. 2; this can also be effected by a pull on wire 46a.

Attention is called in particular to the following features:

(A) The drum has inclined helical or inclined gear teeth 18 as shown most clearly in Fig. 9 and pinion 25 has correspondingly inclined teeth and is not freely rotatable on pivot 24 but is provided with means such as the compressed felt 26 that produces a friction drag which is sufficient to pull the drum away from the magnets 23 if the cable is jerked with sufficient force to start the drum quickly.

The use of the helical or inclined gear teeth to produce the locking force is also believed to be novel in this type of device as well as the means for controlling the frictional resistance to rotation of pinion 25.

5 The use of the type of spring motor shown and de-

scribed is important for the reason that it is compact, light, exerts a substantially constant force throughout its entire range and fits into the same annular space as pinion 25.

Special attention is directed to the means for moving the drum from upper or unlatched position to the lower or latched position shown in Figures 2, 2a, 4 and 5.

What is claimed as new is:

1. A safety anchoring device of the class described comprising a base having a pivot projecting upwardly therefrom, a ring of ratchet teeth surrounding the pivot in coaxial relation thereto, a cylindrical drum having a central hub mounted for rotation on said pivot, the drum having a peripheral wall spaced from the hub to provide an annular chamber, the concave surface of said wall having helical gear teeth forming an internal helical gear, the edge of the wall facing the base having ratchet teeth positioned for operative latching engagement with the ratchet teeth on the base when the drum is in its lowermost position, a permanent magnet carried by the base in position to be operatively engaged by the lower end of the hub when the drum is in latched position, a stationary pivot projecting upwardly from the base into said annular chamber, a helical pinion mounted on the last named pivot in position to operatively engage the teeth on the internal gear, an adjustable friction means operatively positioned between the pinion and the last named pivot for providing an adjusted resistance to turning of the pinion, a cover enclosing the drum, at least one permanent magnet carried by the cover in position to support the drum in raised unlatched position the outer surface of the drum having a groove, a cable wound about the drum in the groove, means comprising a spring motor positioned in the annular chamber and operatively interconnecting the drum and the base, positioned and arranged to rotate the drum in a direction to wind the cable onto the drum, and manual means for moving the drum from its latching position to unlatched position adjacent the magnet carried by the cover.

2. A device in accordance with claim 1 in which the friction means comprises a compressible material positioned in an annular space within the pinion immediately surrounding the pivot, and in which means is provided for compressing the material to adjust its friction effect.

3. A device in accordance with claim 1 in which the drum has two parallel grooves in its peripheral surface and in which the manual means for shifting the drum along its pivot, comprises a slide mounted for vertical movement adjacent the outer surface of the drum and is provided with a pin that projects into one of the grooves and in which a means comprising a manually shiftable cam is operatively associated with the slide to move it in a direction to shift the drum along its pivot.

4. A safety device of the class described, for pilot seats

subject to rapid deceleration, forming a connection between a safety harness and the seat, comprising a base for attachment to the seat, a pivot projecting from the base, a drum pivotally mounted on the pivot, said base and drum having drum latching means comprising opposed ratchet teeth, a cover for the drum, permanent magnets attached to the cover in position to support the drum in freely rotatable position, the side of the drum facing the base having an annular chamber concentric with the pivot, the inner surface of the wall surrounding the annular chamber having helical gear teeth forming an internal gear, a helical pinion pivotally mounted on the base in position for operative engagement with the internal gear, friction means operatively associated with the base and the pinion, means for adjusting the effectiveness of said friction means to vary its resistance, the drum having a cable groove in its peripheral surface, a cable having one end fastened to the drum and wound about the drum in the groove, the other end of the cable having means for effecting a connection with a safety harness, spring motor means carried by the base, positioned in the annular chamber in operative engagement with the internal gear for exerting a rotary force on the drum in a direction to wind the cable thereonto, said helical gear and pinion forming means for producing a force component in a direction to move the drum towards latching position when the cable is unwound therefrom, whereby when the cable is unwound at a fast rate the drum will be moved into latching position, and manually operable means for shifting the drum along its pivot and for returning the drum to unlatched position.

5. A device in accordance with claim 4 in which the base is provided with a permanent magnet that surrounds the drum pivot in position to attract the drum and hold it in latched position.

6. A device in accordance with claim 4 in which the drum has two grooves in its peripheral surface and in which the means for manually shifting the drum in the direction of its pivot comprises, a slide positioned adjacent the drum for movement parallel to the drum axis, a pin projecting from one side of the slide into one of said grooves, and means comprising a cam member operatively associated with the slide for shifting it in either direction to move the drum from either of its two positions to the other.
